KNITTED FABRIC

Charles Moses, New York, N. Y.

Application January 30, 1936, Serial No. 61,448

3 Claims. (Cl. 66—201)

This invention relates to multiple color knitted fabrics in which the surface of the fabric indicates two, three or more distinct non-plated colors.

Broadly, it is an object of this invention to produce a fabric in which the non-knitting threads are interlocked between the knitted loops comprising the face and back of the fabric.

More particularly, it is an object of this invention to float the threads of which any one section of the fabric is composed across the other sections until the particular threads are called upon to produce a corresponding section and to interlock the floats of said threads between the knitted loops comprising the front and back of the fabric thus eliminating long objectionable floats to produce a more serviceable and firm fabric.

Another object is to produce a more uniform and solid mass of color, if required in a fabric, by so interlocking the non-knitting threads so that a smaller and uniform percentage of color of such non-knitting threads are visible upon the surface of the fabric.

Another object of this invention is to produce a fabric having a more substantial body due to the interlocking of two, four or more non-knitting threads between the knitted loops comprising the front and back of the fabric.

Another object is to produce a new and unique type of fabric by utilizing two or more threads having different textures and woven by my new type of knitting.

Another object is to provide an improved method of knitting whereby the aforementioned results may be accomplished.

The fabric is adapted to be produced on any conventional type of multi-feed knitting machine in which the needles can be moved selectively, either mechanically or manually, to welt, tuck, knit and "cast-off" positions, or other means by which corresponding positions may be obtained.

The terms used throughout the specification and claims are hereby defined and explained to clarify my invention.

The welt position is the position in which the needle does not receive any yarn. The tuck position is the position of the needle in which the yarn is taken and held until it is desired to be "cast-off". The knit position is the position of the needle in which the latch of the needle clears all threads, such threads remaining on the shank of the needle, except that a single knitting thread which is being fed-in remains for the time being slightly above the hinge of the latch of the needle.

The "cast-off" position is the position of the needle in which all the yarn on the shanks of the needles

are released and the single thread of the knit position forms a needle wale or stitch, which is held by the hook of the needle.

For the purpose of describing this invention, the loop formed by the needle drawing down the thread W1, "casting-off" the thread running between numbers 24 and 25, I prefer to call the needle wale as shown in Figures 1 and 2. The loop formed by W1 passing over the sinkers between numbers 25 and 26, I prefer to call the 10 sinker-wale, also shown in Figure 1.

A welt sinker-wale is formed by the thread being laid over the sinkers, and the needles between such sinkers remaining in welt position, thus not receiving the yarn and therefore not distorting the 15 sinker-wale which remains in a straight horizontal position, thereby joining the two adjoining needle wales, as shown between points 25 and 26 of Figure 1.

A tuck sinker-wale such as 40 and 41, as shown in Figure 2, is formed by the threads being laid over the sinkers, the needles between such sinkers remaining in a tuck position, thus drawing the 20 yarn from a horizontal position and holding such yarn until "cast-off", and forming an oblique 25 sinker-wale.

For a fuller understanding of the nature and objects of this invention, reference is had to the following detailed description in connection with the accompanying drawings, in which:

Figure 1 shows the back of the fabric of a piece of the knitted cloth consisting of three threads, all greatly enlarged, in which the non-knitted yarns are interlocked between the welt sinker-wales and needle wales.

Figure 2 shows the back of the fabric of a piece of the knitted cloth consisting of three threads, all greatly enlarged, in which the non-knitting threads are interlocked between the tuck sinker-wales and needle-wales.

Figure 3 is a combination of the weaves shown in Figures 1 and 2.

Referring to Figure 1 of the drawings, W1 represents a white thread, for the purpose of illustration, which is knitted in needle-wales 10, 12 and 14, formed by the knitting needles drawing thread W1 to "cast-off" and welt sinker-wales 11 and 13 are formed by the thread W1 passing over the sinkers, known to those familiar with the knitting art, the needles being in a welt position. Thread W1 is interlocked at point 21 by sinker-wale of thread R2 and at point 23 by sinker-wale of thread R1 and is then carried on in the back of the sections Y and Z as a non-knitting thread interlocked by welt sinker-wales of thread R2 and needle-

wales of thread R1 between points 29—30—31—32 and by welt sinker-wales of thread B2 and needle wales of thread B1 between points 34—35—36 and 37.

5 For the purpose of carrying through a knitted course, I will select thread R1, through section X, and trace this thread R1 through section Y, where said thread forms needle wales at the same horizontal level as thread W1 and then through section Z.

10 Thread R1, acting as a non-knitting thread is interlocked at points 38, 39, 40, 41, and 42 between the welt sinker-wales of thread W3, and needle wales of thread W2, and at point 43, thread R1 is interlocked by threads W3 and R2.

15 From point 43, thread R1 becomes the knitting thread through section Y, forming welt sinker-wales 15, 17 and 19 and needle wales 16 and 18. The thread is then interlocked through section Z, 20 by thread B1 at point 44, and at point 45 by thread B and at points 46, 47, 48 and 49 thread R1 is interlocked between welt sinker wales of thread B2 and needle wales of thread B1.

25 Thread B1, follows directly below the thread R1 and is similarly interlocked as thread R1 through section X. From point 43, thread B1 is interlocked by thread W2, at point 50. At points 51, 52, 53 and 54, thread B1, is interlocked between welt sinker-wales of thread R3 and needle wales of thread R2. At point 55, the thread B1 is interlocked by thread R2 and thread B1 then becomes a knitting thread through section Z, forming needle wales 20 and 22 and welt sinker-wales 21 and 23.

30 35 Thread W2 is the knitting thread through section X, forming welt sinker-wales 10, 12 and 14 and needle wales 11 and 13. At point 56, thread W2 is interlocked by thread R2 and at point 57 by thread R1. Thread W2 follows directly above the thread B1 and is similarly interlocked as thread B1, through section Y. At point 58, thread W2 is interlocked by thread B1 and at point 59 by thread R2 and at point 61 by thread B2 and at points 60, 62, 63, 64 and 65, thread W2 40 is interlocked between sinker-wales of thread B3 and needle wales of thread B2.

45 Thread R2, is interlocked at points 66, 67, 68 and 69 between welt sinker-wales of thread W4 and needle wales of thread W3, and at point 43, thread R2 is interlocked by thread W3. From point 43, thread R2 becomes the knitting thread through section Y, forming needle wales 15, 17 and 19 and welt sinker-wales 16 and 18. The thread R2, follows directly below thread W2 and 50 is similarly interlocked as thread W2, through section Z.

55 Thread B2, follows directly below the thread R2, and is similarly interlocked as thread R2, through section X. At point 71, thread B2 is 60 interlocked by thread R3 and at points 70, 72, 73, 74, 75 and 77, the thread B2 is interlocked between welt sinker-wales of thread R4 and needle wales of thread R3. At point 76, the thread B2, is interlocked by thread B3. The thread B2 then 65 becomes the knitting thread through section Z, forming welt sinker-wales 20 and 22 and needle wales 21 and 23.

70 The aforementioned descriptions trace only six threads of three colors through three sections, X, Y, and Z, as shown in Figure 1, namely threads W1, R1, B1, W2, R2 and B2.

75 The following group of six threads are knitted in the same manner as the six threads above described and the next successive group of six threads are knitted in the same manner and a

following group of six threads are similarly knitted and such knitting threads follow on ad infinitum. The sections X, Y and Z have been arbitrarily chosen and may be of different widths than shown in Figure 1 and follow vertically for 5 the complete circumference or width of the knitted fabric woven on the various well known knitting machines used in the art.

10 Referring to section X in Figure 2 of the drawings, W1 represents a white thread for the purpose of illustration, which is knitted into needle-wales formed by the knitting needles drawing the thread W1 to "cast-off" and tuck position, and tuck sinker-wales formed by the thread W1, 15 passing over the sinkers. Thread W1 is interlocked at point 27 by thread R2 and at point 28 by thread R1 and is then carried in the back of section Y and Z as non-knitting threads, interlocked between tuck sinker-wales and needle wales of the thread R2 and needle wales of thread R1 at points 29, 30, 31, 32 and 34 and by thread R1 at point 33 and between tuck sinker-wales and needle wales of thread B2 and needle wales of thread B1 at points 35, 36, 37 and 38.

20 For the purpose of carrying through a knitted course, I will select thread R1 which acts as a non-knitting thread, through section X and trace this thread R1 through section Y, where said thread forms needle-wales at the same horizontal level as thread W1, and then through section Z 25 where it acts as a non-knitting thread.

25 Thread R1 is interlocked at points 39, 40, 41, 42, 43 and 45 between the tuck sinker-wales and needle wales of thread W3 and needle wales of thread W2, and at point 44, thread R1 is interlocked by thread R2.

30 From point 45, thread R1 becomes the knitting thread for section Y, forming tuck sinker-wales and needle wales. The thread R1, follows directly below thread W1 and is similarly interlocked as 40 thread W1, through section Z.

35 Thread B1, follows directly below thread R1 and is similarly interlocked by thread R1 through section X. At point 45, thread B1 is interlocked by thread W3. At points 46, 47, 48 and 49, 45 thread B1 is interlocked between tuck sinker-wales and needle wales of thread R3 and needle wales of thread R2. Thread B1 then becomes a knitting thread through section Z forming needle-wales and tuck sinker-wales.

40 Thread W2 is the knitting thread through section X, forming tuck sinker-wales and needle wales. At point 44, thread W2 is interlocked by threads R1 and R2, and at point 45 by threads R1 and W3. Thread W2, then follows directly above the thread B1 and is similarly interlocked as thread B1, through section Y. At point 50, thread W2, is interlocked by thread B1; the thread W2 is interlocked through section Z, between tuck sinker-wales and needle wales of thread B3 and 60 by needle wales of thread B2, at points 51, 52, 53, 54 and 55. At point 56, thread W2, is interlocked by thread R2, and at point 57, thread W2 is interlocked by thread B2.

65 Thread R2, is interlocked at points 58, 59, 60, 65 61 and 62 between tuck sinker-wales and needle wales of thread W4 and by needle wales of thread W3. At point 63, thread R2 is interlocked by thread W3. From point 63, thread R2 then becomes the knitting thread through section Y, 70 forming needle-wales and tuck sinker-wales. The thread R2, follows directly below the thread W2, and is similarly interlocked as thread W2, through section Z.

75 Thread B2, follows directly below thread R2,

and is similarly interlocked as thread R2, through section X. At point 66, thread B2, is interlocked by thread R3. At points 65, 67, 68, 69, 70 and 71, thread B2, is interlocked by the tuck sinker-wales and needle wales of thread R4 and by the needle wales of thread R3, and at point 72, thread B2 is interlocked by thread B3. The thread B2, then becomes the knitting thread through section Z, forming tuck sinker-wales and needle 10 wales.

The aforementioned description traced only six threads of three colors through three sections, X, Y and Z, as shown in Figure 2, namely, threads W1, R1, B1, W2, R2, and B2.

15 The following group of six threads are knitted in the same respect as the six threads, above described, and the next successive group of six threads, are knitted in the same manner and the following group of six threads are similarly 20 knitted, and such knitting threads follow on ad infinitum. The sections X, Y and Z have been arbitrarily chosen and may be in different widths than shown in Figure 2, and so vertically for the complete circumference of width of the knitted 25 fabric knitted on the various well known knitting machines used in the art.

Figure 3 shows one section of the back of a piece of the knitted cloth consisting of three threads, all greatly enlarged, in which the non-knitting threads are interlocked between the sinker-wales and needle-wales, comprising the front and back of the fabric. The interlocking of the non-knitting threads between the needle 30 wales and sinker wales is a combination of the manner of interlocking the non-knitting threads, as shown in Figures 1 and 2. Section Z, as shown in Figure 3, is a similar section as section Z, as shown in Figures 1 and 2 and the characters which designate the threads are similar to the 35 character designation of the threads in Figures 1 and 2.

For the purpose of clarifying Figure 3, to show the combination of weaves of Figures 1 and 2, showing the manner of interlocking the non-knitting threads between the needle and sinker-wales, I choose to describe the interlocking of non-knitting thread W4, through section Z. Thread W4 is interlocked between the needle-wale 21 of thread B4 and welt sinker-wale 21 of thread 40 B5 in Figure 3 in a similar manner as thread W4 is interlocked by needle wale 21 of thread B4 and welt sinker wale 21 of thread B5, as shown in Figure 1. Thread W4 is then interlocked between tuck sinker-wale 23 of thread B5 and needle wale 23 of thread B4 in Figure 3 in a similar manner as thread W4 is interlocked by tuck sinker wale 23 of thread B5 and needle wale 23 of thread B4 as shown in Figure 2. It is not my 45 intention to limit the combination of altering 50 welt and tuck sinker-wales, as shown in Figure 3 but to any combination which will give certain desired predetermined patterns.

While the fabric has been described with three threads representing different colors, it will be 55 apparent that the three yarns may be identical or have some individual characteristics other than difference in color, such as glossy texture, a loose resilient thread, a dull twisted thread, a 60 silk and cotton or wool combined thread, a thin and thick combined thread, a crinkled thread and so forth. It is also to be understood that the use of three independent yarns represent merely 65

a preferred embodiment and is not intended to act as a limitation.

The term "thread" or "yarn" as used in the specification is intended to include threads of any type regardless of the material of which the 5 same are composed or the cross-sectional contour of the same. Since certain changes in the construction of the above fabric may be made without departing from the scope of this invention, it is intended that all matter contained in the above 10 description shall be interpreted as illustrative and not in a limiting sense.

Although Figures 1, 2 and 3 show different variations of knitting, I would like it definitely understood that the knitting as described in the 15 above figures, is knitted by the same new principle I have evolved.

Heretofore, in fabrics knitted in multi-colors or threads of different characteristics, the non-knitting thread, for a particular section, is first 20 held by the needles in either tuck or welt positions and then "knitted-off", all at the same time, thus forming the so called objectionable floats at the back of the fabric of the non-knitting thread.

In my method of knitting, the non-knitting 25 thread is held in either tuck or welt or a combination of both tuck and welt positions, but instead of "casting off" all the needles at the same time, I "cast-off" only certain predetermined 30 needles at any given time, holding the non-knitting thread on the other needles in either tuck or welt, or the combination of both tuck and welt positions.

At subsequent predetermined periods, I "cast-off" the non-knitting yarns held by either the 35 tuck, welt, or the combination of both tuck and welt needles, the non-knitting threads being interlocked between the tuck or welt sinker-wales and needle wales. By my method of knitting, the objectionable floats of the non-knitting threads 40 are placed between the sinker and needle wales, thereby forming a firm fabric free from any objectionable "floats". By my method above described, I can produce multi-colored and different 45 textured surfaces in predetermined patterns so that colors or textures can appear at different points on the fabric, near or far apart, without having long objectionable "floats" since the non-knitting threads are interlocked between the front and the back of the fabric.

50 I claim:

1. A knitted fabric comprised of a plurality of threads, each thread being knitted in alternate wales and floated past intervening wales in a part of the fabric and being incorporated unknit in 55 an undulating manner under the floats of another thread in another part of the fabric.

2. A knitted fabric comprised of a plurality of threads, each thread being knitted in a section in alternate wales and floated past intervening 60 wales, the floats of the intervening wales holding the other unknit threads in said section in an undulating manner between said floated thread and the looped thread in said intervening wale.

3. A knitted fabric comprised of a plurality of 65 threads, each thread being knitted in alternate wales and floated past intervening wales in a part of the fabric and being incorporated unknit alternately in an undulating manner in one wale and in a straight manner in the following wales 70 under the floats of another thread in another part of the fabric.
